(57) **CLAIM**

The ornamental design for a lamp, as shown and described.

DESCRIPTION

FIG. 1 is a top perspective view of a lamp;

FIG. 2 is a front view thereof; the back view, left-side view, and right-side view are identical to the corresponding view illustrated in FIG. 2;

FIG. 3 is a bottom view thereof; and,

FIG. 4 is a top view thereof.

The dashed broken lines depict portions of the lamp that form no part of the claimed design.
